KENNETH E. BREWER, OF CHICAGO, ILLINOIS, ASSIGNOR TO CHAS. A. BREWER & SONS, OF CHICAGO, ILLINOIS, A PARTNERSHIP COMPOSED OF NELSON C. BREWER, KENNETH E. BREWER, AND EVERETT R. BREWER

GAME BOARD

Application filed July 10, 1930. Serial No. 466,900.

This invention pertains to a class of amusement devices commonly known as game boards, and more particularly to a type of game board going by the general designation of a "punch board". These "punch boards" contain a plurality of sealed pockets or cells, similar to honey-comb, which cells contain folded or rolled slips of paper or the like, each bearing a different number or legend and adapted to be ejected from its cell by a pin or punch that slidably fits the cell. The slips may contain questions relating to geography, history, popular science, current events, advertising slogans, sports, the Bible, literature, or a wide range of other popular information. A key or answer slip usually accompanies the board and contains answers to the questions written on the slips.

In one known structural form of these game boards, the body of the board has consisted of a stack of cardboard or pasteboard sheets of equal sizes, in all of which holes have been punched in the same relative positions, the boards being superposed and pasted together with the registering holes forming the slip pockets or cells, sealing sheets being applied to the opposite sides of the board to lock the slips in the pockets. In the manufacture of such boards, considerable difficulty has been experienced due to expansion and contraction of the material used in the punched sheets that are laminated together; unequal contraction and expansion of the several sheets frequently resulting in throwing the holes thereof out of perfect register. Furthermore, where the entire body of the board is thus made of cardboard, pasteboard, or like material, the board, under varying moisture conditions of the atmosphere, will sometimes warp, thus rendering it difficult to eject the paper slips from the cells or pockets of the board.

The main object of the present invention has been to improve boards of this character in the way of insuring accurate registration of the holes of the superposed sheets so as to provide straight and uniform cells or pockets. Another object has been to provide a construction which will prevent swelling, shrinking and warping of the board, and

give it a stronger and more rugged character.

Still another object is to provide a construction which will strengthen the walls between the holes of the board.

With these objects in view, I have designed the novel structure of the present invention, the chief novel feature of which resides in interposing or interspersing among the perforated cardboard sheets of the laminated board similarly perforated thin metal sheets, which latter are not subject to swelling and shrinking under atmospheric conditions and the perforations of which have marginal burrs countersunk into the margins of the holes of each underlying cardboard sheet and tend to maintain the uniformity and integrity of the cardboard sheets.

The invention will be further explained in detail in connection with the accompanying drawings, illustrating the same, in which—

Fig. 1 is a perspective elevation of a game board embodying my present invention.

Fig. 2 is an enlarged fragmentary transverse section through one row of holes, illustrating the cardboard-metal laminated structure.

Fig. 3 is a fragmentary view illustrating a slight modification of Fig. 2.

Fig. 4 is a much enlarged detail view of a single metal and cardboard sheet pasted together and showing an automatic locking feature.

Referring to the drawings, A in Fig. 1 designates the game board as an entirety. Referring to Fig. 2, the body of the board consists of superposed sheet units, each unit consisting of a thin metal sheet 2 and an underlying cardboard sheet 3, the two sheets being pasted or glued together. By means of a suitable punch, each sheet is formed with longitudinal and transverse rows of holes 4, which latter, when the sheet units are superposed and adhered, form the slip pockets or cells 5 (Fig. 1) extending entirely through the body of the board. The front and back sides of the board body are covered with imperforate thin sealing sheets 6. In order to provide the necessary stock for the formation in one edge of the board of a key pocket, 100

such as shown and described in Letters Patent to Chas. A. Brewer, No. 1,309,349, July 8, 1919, I may apply to the back side of the board two extra sheets of cardboard 3' lying on opposite sides of the rear sealing sheet 6, but this feature is immaterial to the present invention.

Instead of building the board up of alternating cardboard and metal sheets, as shown in Fig. 2, each sheet unit may consist, as shown in Fig. 3, of a thin metal sheet 7 and two cardboard sheets 8, respectively, adhered to the two sides of the metal sheet. This construction fulfills the purposes of the invention, and is slightly less costly than that of Fig. 2 because of employing a lesser number of metal sheets in the structure. The metal which I have found best suited for the purposes of the invention is aluminum, but thin sheet tin is also satisfactory.

9 designates a marginal binding for the board which may consist of adhesive tape or a thick lacquer; but with this feature of the board, the present improvement is not concerned.

In preparing the sheet unit, which, as above stated, consists of a metal sheet and a cardboard sheet (Fig. 2), or a metal sheet interposed between two cardboard sheets (Fig. 3), the sheets are first pasted together face to face and then placed beneath the punching machine which forms the holes. Referring to Fig. 4, it will be seen that in the punching operation I create an annular fin or bur 2' on 30 the edge of the opening in the metal sheet, the purpose of this fin or bur, which sinks into the underlying cardboard sheet, being to interlock the cardboard and metal sheets securely against displacement in an edgewise direction. This feature also assists in maintaining the perfect registration of the holes in the metal and cardboard sheets, thus contributing to the uniformity and smoothness of bore of the cell pockets, and also performs 40 another important function in stiffening and strengthening the intervening walls between the cell pockets.

By constructing the sheet units in the manner above described, I have found that when 50 assembling them to form the board, the registration of the holes is more perfect than where cardboard or pasteboard sheets alone are used, and consequently the manufacturing operations are simplified, and the board itself 55 is a more perfect structure than heretofore. Furthermore, the metal sheets interspersed throughout the board prevent warping and also slight lateral displacements of adjacent sheets, which, in the laminated structures 60 heretofore known, marred the perfection of the cell pockets.

I claim:

A laminated game board of the character described, comprising interspersed cardboard and metal sheets disposed face to face

and glued together, said sheets formed with registering holes together forming pockets extending through said board, the holes in each metal sheet having marginal burs countersunk into the margins of the holes in the underlying cardboard sheet thereby locking said sheets together edgewise, and sealing said sheets covering the ends of said pockets.

KENNETH E. BREWER.
